ROLL PROTECTION

Valerie F. Blake, New York, N. Y.

Application January 31, 1933, Serial No. 654,407

10 Claims. (Cl. 206—59)

This invention relates to the protection of the ends and corner edges of heavy rolls of paper and the like. The objects of the invention are to provide a protector for roll ends, which can be quickly and easily applied to rolls of different diameters; which will securely hold to its protecting position on the roll and which, when desired, can be readily removed and which, possessing the above and other desired characteristics, will be relatively inexpensive, practical and of a form which may be packed and shipped in convenient compact shape.

The foregoing and other desirable objects are attained by the novel features of construction, combinations and relations of parts hereinafter described and broadly covered in the claims.

The drawing accompanying and forming part of the specification illustrates one practical commercial embodiment of the invention, it being understood that the structure may be modified and changed without departure from the true spirit and broad scope of the invention.

Fig. 1 is a perspective view illustrating a roll of paper or the like, having the protectors applied thereto and showing at one end the mode of application and also illustrating the easy-removal feature.

Fig. 2 is an enlarged broken sectional detail as on line 2—2 of Fig. 1, showing the layers of protector about the corner edge of the roll.

Fig. 3 is a broken face view of the end disc portion of the protector.

Fig. 4 is an enlarged sectional detail of the same as on line 4—4 of Fig. 3.

Figs. 5 and 6 are broken plan and cross-sectional views of the outside protector strip, the latter view appearing as on line 6—6 of Fig. 5.

In Fig. 1, the protectors are shown applied to a heavy roll of paper or the like, designated 7.

The protector consists in this disclosure of a disc 8, of cardboard, heavy paper, or the like, of a diameter approximating that of the roll to which it is to be applied and having at its rim projecting lugs, lobes or scallops 9, adapted to be turned over and secured to the circumferential portion of the roll as indicated in Fig. 1.

The end disc may be scored as indicated at 10, in Fig. 3, to provide a hinging axis at the juncture of the tabs or segments with the rim of the disc and these tabs themselves may be scored as indicated at 11, to permit adjustments for over-size rolls. Only the end portions of these securing tabs may be glued or cemented as indicated at 12, and this may be a quick drying cement put on at the time of applying the disc to the roll, or it

may be applied to the tabs in the course of manufacture and then be wet at the time of applying the disc to the roll.

If desired, the body portion of the end disc may be adhesively secured to the end of the roll, though ordinarily the adhesion of the tabs to the roll circumference is usually sufficient for securing purposes.

At the center, the end disc is shown as perforated at 13, in line with the opening 14, through the core of the roll, so that the roll may be mounted on a mandrel or the like, with the protector still in place.

For quick removal purposes, the disc may be scored, perforated, or otherwise weakened as on radial lines as indicated at 15, to enable the disc being torn away in segments as appears in Fig. 1. The mandrel opening 13 provides access to the inner ends of these segmental portions, which can thus be readily grasped in the fingers and torn outwardly on the weakened lines. In the illustration, only four tearing lines are shown, enabling the end disc to be torn away in quarters, but it will be obvious that more lines may be provided, if considered desirable, which may be the case where the disc is of relatively heavy cardboard.

After the end disc is in place and secured by the circumferential tabs, an outer protecting member may be applied, the same consisting of a strip 16 of cardboard, heavy paper, or the like, which is adhesively secured over the circumferential tabs 9, and has along one edge the projecting scallops or lugs 17, which are turned inward and adhesively secured over the face of the end disc. This strip protector serves the purpose of locking the attaching tabs of the end disc down over the circumference of the roll and of reinforcing the corner portion of the roll, as in Fig. 2, where it will be noted that the slotted or cut portions of one member, come opposite a solid portion of the other member, so that the weakest part of one is reinforced by a solid part of the other. Thus, the slotted circumferential portion of the disc member is covered and bound together by the solid strip portion 16 of the outside member and the slotted or scalloped portion of the outer member is reinforced and tied together by the solid end part 8 of the disc member.

The protector is easily applied by placing the disc over the end of the roll and securing the tabs of the same over the circumference of the roll, these tabs bending on the proper hinge lines 10, 11, to fit the diameter of the particular roll; the circumferential portion 16 of the strip mem-

ber is then secured over the tabs of the end disc and the lugs 17 turned in and secured over the edges of the disc. The openings 13 in the end discs enable a mandrel or other implement to be inserted in the roll, before removing the protectors and these openings also enable the disc to be grasped at the center portion and torn away on the weakened line or lines 15. In this removal operation, these tears can be extended 10 through the outer protecting strip, the notches between the flaps 17, enabling such tears to readily run clear out to the circumferential strip 16, whereupon the torn away segment serves as a lever or handle portion to tear away the final 15 circumferential portion 16.

The outer protecting strip may have hinging lines 10a and 11a, substantially as indicated in Figs. 5 and 6, at the roots of the tongues or tabs, and in the length of the tabs themselves and it will be noted in these views, that the cuts or 20 notches 18 which separate and define the tabs or scallops, terminate short of the hinging line 10a to avoid weakening or tearing of the body portion 16 of the strip. Similarly, the notches 25 19 in the perimeter of the disc, defining the tabs 9, terminate short of or do not intersect the bead or score line 10, so as to leave these tabs strongly attached to the body of the disc. The tearing lines 15 may extend from the mandrel opening 30 13, substantially out to the hinging line 10 and preferably in line with notches between the tabs.

What is claimed is:

1. A roll end protector, comprising a disc of cardboard or the like, applicable over the end of a roll and having a scalloped periphery providing edge tabs adapted to be bent down over the adjoining circumferential portion of a roll, a circumferential strip engaging said tabs and having a scalloped edge providing tabs engageable over the face of the disc, said disc and said strip each having plural hinging lines for the tabs enabling adaptation of the same to fit different size rolls.

2. A roll end protector, comprising a disc of cardboard or the like, applicable over the end of a roll and having a scalloped periphery providing separated edge tabs adapted to be bent individually down over the adjoining circumferential portion of a roll, a circumferential strip engaging said tabs and having a scalloped edge providing tabs engageable over the face of the disc, said end disc having lines of weakness extending from the central portion toward the periphery of the same to enable the protector being readily torn away from a roll and said disc having a central 55 opening from which the lines of weakness extend.

3. In a roll protector, a disc of cardboard or the like, said disc having a central opening and a line or lines of weakness extending outwardly from said central opening.

4. In a roll protector, a disc of cardboard or the like, said disc having a central opening and a line or lines of weakness extending outwardly from said central opening, said disc having a notched peripheral portion providing independently bendable tabs engageable over the circumferential portion of a roll.

5. In a roll protector, a disc of cardboard or the like, said disc having a central opening and a line or lines of weakness extending outwardly from said central opening, said disc having a notched peripheral portion providing independently bendable tabs engageable over the circumferential portion of a roll and said disc having a plurality of hinging lines for said tabs, to enable the fitting of the same to rolls of different 20 diameters.

6. A roll protector, comprising a disc having an annular bead defining a hinge line and notches extending inwardly short of said bead and defining attachment tabs bendable on said hinge 25 line, said tabs themselves being scored to provide additional hinging lines.

7. A roll protector, comprising a disc having an annular bead defining a hinge line, notches extending inwardly short of said bead, defining 30 attachment tabs bendable on said hinge line, said disc having a central tearing opening and a line or lines of weakness extending from said tearing line outwardly to said hinge bead.

8. A roll protector, comprising a disc having an annular bead defining a hinge line, notches extending inwardly short of said bead, defining attachment tabs bendable on said hinge line and a binding strip secured over said tabs and having tabs secured over the end disc.

9. In a roll protector, a strip of cardboard or the like, scalloped along one edge and having a longitudinally extending bead defining a hinging axis for the scallops and said scallops having beads extending thereacross defining additional hinging axes.

10. In a roll protector, a roll end engaging disc of cardboard or the like, said disc having a notched periphery providing separate bendable tabs and further having a central opening with a line of weakness extending radially outwardly from said central tearing opening in line with a notch aforesaid.
